UNITED STATES PATENT OFFICE

105,327

DESIGN FOR A SIDE WALL LIGHTING FIXTURE OR THE LIKE

Edward C. Godfrey, Detroit, Mich.

Application March 4, 1936, Serial No. 61,470

Term of patent 7 years

To all whom it may concern:

Be it known that I, Edward C. Godfrey, a citizen of the United States, residing at Detroit, county of Wayne, State of Michigan, have invented a new, original, and ornamental Design for a Side Wall Lighting Fixture or the like, of which the following is a specification, reference being had to the accompanying drawing, forming part thereof.

The figure of the drawing is a perspective view of a side wall lighting fixture showing my new design.

I claim:

The ornamental design for a side wall lighting fixture or the like as shown.

EDWARD C. GODFREY.
